UNITED STATES PATENT OFFICE

HARRY HOWARTH, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

FEELER TO STOP LOOM

Application filed March 27, 1929. Serial No. 350,416.

This invention relates to improvements in stopping mechanism for looms and it is the principal object of the invention to provide improved means for stopping the loom prior to the complete exhaustion of weft in the running shuttle.

It is a further object of my present invention to provide a simple form of connection between the weft detector and the loom stopping mechanism, said mechanism comprising a minimum number of parts and operating preferably on the indicating stroke of the lay to stop the loom.

It is a still further object of my present invention to provide knocking-off mechanism so related to the weft detector that the weight of said mechanism acts to return the detector to normal position after an indicating movement thereof.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is an end elevation of a portion of a loom having my invention applied thereto, the lay and certain parts carried thereby being in section,

Fig. 2 is a top plan view of a portion of a mechanism shown in Fig. 1, parts being broken away for purposes of illustration,

Fig. 3 is a vertical section on line 3—3 of Fig. 1,

Fig. 4 is a top plan view taken in the direction of arrow 4, Fig. 3, the detector being shown in indicating position and a portion of the cover being removed, and

Fig. 5 is a view similar to a portion of Fig. 1, indicating the operating movements of the detector controlled mechanism.

Referring to Figs. 1 and 2, I have shown a loomside 10 in which is mounted for rotation a shipper rod 11. A shipper handle 12 moves pivotally about the rod 11 and has a cam slot 13 in the ends of which are notches 14 and 15, respectively. A shipper lever 16 has an upwardly extending lug 17 which ex-

tends into the slot 13 and is proportioned to enter the notches, depending upon the position of the shipper handle 12. When the parts are in the position shown in Fig. 1, the lever 16 will be moved to disconnect the driving mechanism not shown from the loom, but when the shipper handle is moved to the left or forwardly, as viewed in Fig. 1, said lever 16 will be moved to apply the power to the

A brake lever 18 is pivoted to the shaft 11 and has a horizontal rearwardly projecting arm 19 which is pivotally connected as at 20 to the forward end of a brake controlling rod 21. The arm 19 has a depending finger 22 from which extends a set screw 23 positioned to engage that portion of the shipper handle 12 which is below the rod 11. When the brake is off the handle 18 will be in the position shown in Fig. 1, the center of the pivotal connection 20 being slightly above a line joining the axis of rod 11 and the axis around which the rear end of the brake controlling rod 21 moves. I have not shown herein the particular brake mechanism to which the rod is connected, but the same is well understood and the parts are so related that the rod 18 is held in the position shown in Fig. 1 because of the relation of stud 20 with respect to the rod 11 and the connection of the rod 21 with the braking mechanism.

A bracket 24 is secured to the loomside and has rotatably mounted therein a rock shaft 25 longitudinal motion of which in one direction is limited by a collar 26 held to the shaft by a set screw 27.

A bracket 28 secured to the loom frame supports the base 29 of a weft detecting mechanism designated generally at D. As shown more particularly in Figs. 3 and 4 the detector mechanism comprises a bed 30 having a forwardly extending groove 31 in which is slidably mounted a detector carrier 32. The detector 33 which directly engages the bobbin is pivoted on a stud 34 mounted on the carrier. The arm has a forwardly extending tail 35 and is normally held rearwardly by means of a compression spring 36 the rear end of which engages the detector as at 37 and the forward end of which engages

a wall 38 of the bed 30. The effect of spring 36 is to hold the carrier 32 and detector 33 yieldingly in rearward position. A cap 39 may be employed to prevent improper upward movement of the detector carrier and 5 spring.

As shown in Fig. 3 the base 29 is provided with a stud 40 on which is pivoted an indicating lever 41 having an upwardly extending arm 42 which lies in the path of the 10 tail 35.

Under normal conditions the shipper and brake levers will be in running position and as the lay moves forwardly with a full supply of weft W the detector 33 and carrier 32 15 will move forwardly without relative angular movement, the arm 42 of the indicating lever 41 remaining at rest. When insufficient yarn remains on the bobbin, however, the detector 33 will move to the right as 20 shown in Fig. 4, the tail 35 moving to the left around the stud 34 to rock the indicating lever 41 from the dotted to the full line position shown in Fig. 3.

The matter thus far described is well-known and forms no part of my present invention, the shipping and braking mechanism being the same as that used for a number of years on a commercial form of non-automatic loom and the detector being of the 30 form shown in the application Ser. No. 200,481.

In carrying my invention into effect I provide simple connecting mechanism between the detector and the brake lever 18. 35 I form the latter with a forwardly extending arm 50 having adjustably secured therein a stop screw 51 the lower end of which is provided with a rounded head 52. I secure to the rock shaft 25 a knock-off member 53 having an upwardly facing surface 54 for engagement with the head 52. The knock-off member is provided with a depending arm 55 to which is pivoted as at 56 a rod head 57. The latter has adjustable connection with a rearwardly projecting dagger or controller 58 which is supported partly by means of a link 59 shown more particularly in Fig. 3. Link 59 has the lower end thereof bent upwardly 40 to form a hook 60 to receive the rear end of the dagger 58. The upper end of said link is connected as at 61 to an arm 62 formed integral with the indicating lever 41.

The lay L which may be of usual construction to receive a shuttle S has a small bracket 63 secured to the front face thereof, and said bracket is provided with a vertical slot 64 through which extends the threaded end 65 of a bunter 66. The latter is held in adjusted position with respect to the lay by means of a pair of check nuts 67.

So long as a sufficient supply of weft is present in the running shuttle the dagger or controller 58 will lie below the bunter. When 65 the weft is exhausted, however, the indicat-

ing lever 41 will rock to the full line position shown in Fig. 3, as previously described, thereby lifting the dagger 58 to the position shown in Fig. 5, where it will be in the path of the advancing bunter 66. The latter will engage the dagger shortly before the lay reaches its extreme forward position and as the lay completes its forward stroke, the dagger will move forwardly and thereby cause rocking of the knock-off member 53. 70 The surface 54 of the latter will thereupon lift the head 52 of the nut 51 to effect rocking movement of the brake lever 18 in a clockwise direction around the shipper shaft 11 as viewed in Fig. 1.

As soon as the stud 20 passes a predetermined position in its downward movement the screw 23 will be forced against the lower part of the shipper lever and the latter will be moved from running to stopping position. 80 Under these conditions the brake is applied and the shipper handle acts to move the shipper lever 16 to loom stopping position. It will be noted that this operation takes place during the forward stroke of the lay on the indicating beat of the latter. As soon as the lay is moved rearwardly far enough to effect disengagement between the dagger and the bunter said dagger and the link 59 will act by their weight to restore the indicating lever 41 to normal position and assist 90 also in returning the detector to normal position.

From the foregoing it will be seen that I have provided a very simple connection between the weft detector and a loom stopping mechanism, the connections being effective by their weight to restore the indicating lever to normal position. It will also be noted that the stopping of the loom is effected on the 100 forward stroke of the lay upon which indication of exhaustion is given.

Having thus described my invention it will be seen that changes and modifications may be made therein by those skilled in the art 110 without departing from the spirit and scope of the invention and I do not wish to be limited to the details herein disclosed, but what I claim is:

1. In stopping mechanism for a loom, weft detecting mechanism to indicate the near approach of exhaustion in the active shuttle, a lay, a bunter mounted on and moving forwardly with the lay, loom stopping devices normally in running position, a dagger operatively connected to the devices and normally out of the path of movement of the bunter, an indicating lever to be moved by the detector when the latter gives indication of weft exhaustion in the running shuttle, and connections between the dagger and the lever whereby said lever is effective to lift the dagger into the path of movement of the bunter on indicating beats of the loom to cause said lay during the last part of its 115

forward stroke to move the stopping devices to loom stopping position, the weight of the dagger acting to restore the indicating lever to normal position.

2. In stopping mechanism for a loom, weft detecting mechanism to indicate the near approach of exhaustion in the active shuttle, a lay, a bunter mounted on and moving forwardly with the lay, loom stopping devices normally in running position, a dagger operatively connected to the devices and normally out of the path of movement of the bunter, an indicating lever to be moved by the detector when the latter gives indication of weft exhaustion in the running shuttle, and connections between the dagger and the lever whereby said lever is effective to lift the dagger into the path of movement of the bunter on indicating beats of the loom to cause said lay during the last part of its forward stroke to move the stopping devices to loom stopping position, the weight of the dagger and connections acting to assist in restoring the detector to normal position.

3. In stopping mechanism for a loom, weft detecting mechanism to indicate the near approach of exhaustion in the active shuttle, a side slipping weft engaging element formed as part of the detector mechanism and movable angularly at the time of indication of weft exhaustion, a lay, loom stopping devices normally in running position, a dagger operatively connected to the devices and normally in down position to be out of operative relation with respect to the lay when the latter moves forwardly, connections between the dagger and the element of the detector effective to lift the dagger into cooperative relationship with the lay on indicating beats of the loom when the detector element moves angularly, to cause the lay to move the devices to loom stopping position, the weight of the dagger being exerted on the backward stroke of the lay following indication to move the detector element angularly back to its normal position.

In testimony whereof I have hereunto affixed my signature.

HARRY HOWARTH.
